ABSTRACT

A high-speed hammer wherein the working tools secured, respectively, on the anvil block and crosshead of a frame perform a working stroke being acted upon by a power unit mounted on the frame, and are returned to the initial position by compressed gas contained in a space in the anvil block.

Said space accommodates a piston whose rod is adjustably connected with a bed for adjusting the position of the frame relative to said bed.

FIG. 2

HIGH-SPEED HAMMER

The present invention relates to working of metals by pressure and more specifically it relates to high-speed hammers.

Known in the art are high-speed hammers comprising a bed with a movably-installed frame carrying a power unit, and working tools moved in the opposite directions by said power unit, said working tools secured, respectively, on the crosshead and anvil block of the frame.

This hammer comprises a device for returning the frame to the initial position and holding it there.

This device consists of power cylinders for lifting the frame to the initial position and a collet chuck for holding it in the upper position, said chuck being located in the anvil block and controlled by a knockout in the course of its movement (see, for example, Author's Certificate No. 196,522, Cl. 49.1).

In this hammer the position of the frame relative to the bed and, consequently, the position of its working zone is not adjusted for height which is sometimes necessary when the hammer is used as a component of a stamping line.

An object of the present invention is to provide a hammer wherein the position of its working zone could be changed to enable said hammer to be used as a component mechanism of a stamping line.

In accordance with this object we hereby provide a high-speed hammer comprising a frame movably installed on a bed, said frame carrying a power unit, and working tools actuated by said power unit for making a working stroke, said tools being secured, respectively, on the crosshead and anvil block of the frame, and a device for returning the frame to the initial position and holding it there wherein, according to the invention, said device is made in the form of a space located in the anvil block, filled with high-pressure gas and accommodating a piston whose rod is adjustably connected by a screw joint with the bed for adjusting the position of the frame for height with relation to the bed.

The high-speed hammer according to the present invention can be used in a stamping line because its design allows its working zone to be adjusted for height.

Now the invention will be described in detail by way of example with reference to the accompanying drawings in which:

FIG. 1 is a general view of the high-speed hammer according to the invention, partly cut away;

FIG. 2 is a section taken along line II-II in FIG. 1.

The high-speed hammer comprises a bed 1 (FIGS. 1, 2) with guides 2 rigidly secured on it. Said guides are fastened to the bed 1 with the aid of wedges 3 which allow adjusting the position of said guides 2.

A frame 6 is secured on the bed 1 by means of a rod 4 (FIG. 1) provided with a piston 5 at the end. The frame 6 is formed by cylindrical stepped uprights 7 which carry an anvil block 8 on the top and a guide cylinder 9 at the bottom, said cylinder accommodating a crosshead 10 which is capable of vertical motion. Installed on the frame 6 under the guide cylinder 9 is a power unit 11.

The ends of the uprights 7 are threaded to receive the nuts 12 which hold together all the above-mentioned elements of the frame.

The anvil block 8 and the crosshead 10 carry, respectively, the working tools 13 and 14 which are consti-

tuted in this example by dies. The anvil block 8 consists of an upper plate 15, lower plate 16 and intermediate plates 17. The die 14 is fastened to the lower plate 16 while the upper plate 15 has a space 18 filled with high-pressure gas and accommodating the piston 5 with the rod 4. The upper threaded end of the rod 4 passes through a hole in the upper plate 19 of the bed 1, being secured to it by a nut 20 and a lock nut 21. This method of rod fastening allows the position of the frame to be changed with relation to the bed 1 when the hammer is used in a production line.

The rod 4 has a channel 22 through which high-pressure gas is delivered from a receiver (not shown in the drawing) into the space 18 for holding the frame in the topmost position.

The plates 17 and 16 have holes forming a through channel 23 used for the passage of a knockout 24 which has a piston 25 at the end, located in the space 26 of the piston 5. This space communicates with a hydraulic drive 28 through a channel 27 in the rod 4.

Adjustable stops 29 (FIG. 2) secured on the bed 1 are intended to prevent probable turning of the frame 6 in a horizontal plane.

In the course of stamping, the working zone of the hammer is closed by an armoured wall 30 (FIG. 1) which is lowered and lifted by power cylinders 31.

The power unit 11 has a combustion chamber 32 for burning the gas-air mixture, a valve 33 and a channel 34 extending from the power unit 11 to the crosshead 10 the latter moving vertically in the guide cylinder 9.

The high-speed hammer operates as follows.

The drawing illustrates the hammer in the initial position. The space 18 is filled with air through the channel 22 in the rod 4 under a pressure required for holding the frame 6 in the topmost position.

A mixture of gas with air is delivered from a charging unit (not shown) into the combustion chamber 32 of the power unit 11 to a certain pressure after which an ignition device (not shown) is turned on. With an increase of pressure in the chamber 32 the forces acting on the valve 33 keep growing too and, when they reach a preset value, the valve 33 operates. The channel 34 is put in communication with the combustion chamber 32.

The pressure of the expanding gases is applied to the lower face of the crosshead 10 and to the bottom of the combustion chamber 32 of the power unit 11.

The crosshead 10 together with the working tool 14 moves at a high speed upward in the guide cylinder 9 and in the guides 2.

The pressure acting on the bottom of the combustion chamber 32 pushes down the power unit 11 and, consequently, the anvil block 8 together with the working tool 13.

The pressure of the expanding gases is converted into the kinetic energy of the working tools 13 and 14 which move towards each other, and is used for stamping the work.

Meanwhile, the gas contained in the space 18 is compressed by the piston 5 when the anvil block 8 goes down and, after the stamping stroke, returns the frame 6 to the initial topmost position and holds it there. The working tool 14 secured to the crosshead 10 returns together with the crosshead 10 to the initial position under its own weight.

The stamped work is discharged by the knockout 24 for which purpose the hydraulic liquid flows from the

hydraulic drive 28 through the channel 27 into the space 26, moving the piston 24 down in said space.

For adjusting the position of the hammer working zone, it is necessary to unscrew the nut 20 and lock nut 21, to set the rod 4 and, consequently, the frame 6 at the required height above the bed 1 and to tighten the nuts 20 and 21 again.

What is claimed is:

1. A high-speed hammer comprising: a bed; a frame mounted on said bed with a provision for vertical motion and consisting of an anvil block and a crosshead

connected to each other; working tools secured, respectively, on said anvil block and crosshead; a power unit mounted on said frame and intended to move said working tools towards each other during the working stroke; a space in said anvil block filled with high-pressure gas for returning the frame to the initial position after the working stroke; a piston located in said space; the rod of said piston connected adjustably with said bed with the purpose of adjusting the position of 10 said frame for height with relation to said bed.
